PIVOTAL FRAME STRUCTURE FOR ROTARY PRINTING MACHINE ELEMENTS

Harold Holmyard Beasley, Bristol, England, assignor to Beasley, French & Company Limited, Bedminster, Bristol, England

Application June 3, 1948, Serial No. 30,857
In Great Britain June 6, 1947

3 Claims. (Cl. 101—216)

1

This invention relates to a construction and arrangement of rotary printing machines of a type in which interchangeable printing cylinders of varying dimensions are used to give a range of printing sizes, circumferences or pitch of impressions on webs of paper, viscose film or other suitable material.

In printing machines of this type as constructed according to present practice it has been usual for the width between the bearings which carry and support the printing cylinder to be greatly in excess of the effective printing width of the machine which is governed by the effective width of the printing cylinder. This excessive width between the supporting bearings of the printing cylinder is necessitated by the various forms of construction usually adopted to enable the printing, impression and inking cylinders to be moved or adjusted in relation to each other to accommodate interchangeable printing cylinders of varying dimensions and to provide space at the ends of the inking cylinders for splash guards, driving gear or other parts.

This excessive width between the supporting bearings of the printing cylinder has hitherto been particularly objectionable in printing machines of this type, as, owing to the unequal distribution and weight of printing plates and type carried thereon, the cylinders are usually out of balance in varying degrees. As a consequence of the widely spaced bearings, the long shafts employed to support the cylinders are liable to whip and set up vibration when running, in a manner very detrimental to the quality of the printing and likely to detract from the useful life of the printing plates. The resulting lack of rigidity also tends to set a limit to the effective running speed of printing machines of this type.

It is a primary object of this invention to provide a construction and arrangement of printing machine of the type described which will obviate these disadvantages. A further object of this invention is to provide additional desirable features not previously attained in printing machines of this type and, as a result printing machines constructed in the manner described hereafter will be extremely compact and rigid and all bearings may be spaced to a width suited to their respective cylinders. The driving gears may be placed outside the frame of the machine and can be effectively guarded and lubricated.

According to this invention the removable printing cylinder is detachably mounted in the fixed frame members of the machine in bearings which are spaced closely to the ends of the cyl-

inder in order to ensure rigid mounting and support of the printing cylinder. The impression cylinder and inking cylinders are carried in bearings mounted in brackets pivotally supported outside the frame members of the machine and adapted to swivel about the axis of the driving gear arranged outside the fixed frame of the machine which transmits the drive to both cylinders and means of adjustment is provided for moving these brackets and the impression and inking cylinders toward and away from the axis of the printing cylinder to accommodate printing cylinders of different diameters which may be interchangeable in the bearings suitably arranged in the fixed frame members of the machine for this purpose.

In a suitable construction the impression and inking cylinders are rotated from a common drive and the brackets carrying the bearings of these cylinders are mounted to swivel about the axis of a common driving gear arranged outside the fixed frame of the machine and adapted to transmit the drive to both cylinders and so that adjustment of the brackets about this axis will not affect the driving engagement of the gears. One or more additional inking cylinders may be supported in bearings in separate brackets arranged to swivel about separate pivotal supports on the main frame of the machine and these brackets may also be connected to each other by adjustable connecting links which maintain the position of the inking cylinders relatively to one another but permit their adjustment relatively to the printing cylinder.

In order that the invention may be more readily understood, a suitable application thereof will now be described with reference to the accompanying drawings in which:

Figure 1 is a side elevational view of the end portion of a rotary printing machine showing how the printing cylinder and the impression and inking cylinders are mounted and driven relatively to each other.

Figure 2 is a part transverse sectional view taken approximately on the line III—III of Figure 1, showing one end of the various cylinders and the bearings and supports at that end, and

Figure 3 is a similar view to Figure 2 showing the other end of the various cylinders with their bearings and supports and also the driving gears.

In a suitable application of the invention as shown in the drawings the frame members of the machine are formed with rigidly supported

bearings 2, preferably located at or near one end of the machine. These bearings 2 are detachable or are split and provided with detachable caps 3 to permit ready removal and replacement of the printing cylinder 4, the shafts 5 of which engage therein. The impression cylinder 6 which may be wider than the printing cylinder 4, has its shafts 7 supported in suitable roller or other antifriction bearings 8, in brackets 9 adjustably mounted to turn about fixed swivel supports 10, outside the frame 1 of the machine. The brackets 9 are formed as quadrants with gear teeth 11, having toothed pinions 12 on a cross shaft 13 gearing therewith and adapted to be rotated by worm 14 and wheel 15 or other suitable adjusting means. An inking cylinder 16 has its shafts 17 mounted in roller or other suitable anti-friction bearings 18 in separate brackets 19 adapted to swivel about the axis of the supports 10, on the frame 1 of the machine and provided with downwardly directed toothed quadrants 20, and a separate shaft 21 with toothed pinions 22 and similar worm and wheel or other suitable adjusting means for rotating the shaft 21. Another inking cylinder 26 has its shafts 27 mounted in roller or other suitable anti-friction bearings 28 in separate brackets 29 having slotted ends 31 adapted to turn about swivel supports 30 on the frame members 1. Extensions of these brackets 29 and the brackets 19 of the first mentioned inking cylinder 16 are connected by adjustable links 32, which enable the relative position of the inking cylinders 16 and 26 to be accurately adjusted relatively to one another. These links 32 are arranged so as to maintain a substantially parallel relationship between the supporting brackets 19 and 29 of the inking cylinders 16 and 26, thus enabling them to be adjusted relatively to the printing cylinder 4, without affecting the adjustment relatively to each other.

In the example shown in the drawings the drive to the impression cylinder 6 and one inking cylinder 16 is provided by a common driving gear 40 mounted to rotate about the axis of the common pivot 10 of the brackets 9 and 19 supporting these cylinders 6 and 16. The common driving gear 40 is rotated by the main driving wheel 41 and gears with a toothed wheel 42 on the shaft 7 of the impression cylinder 6 and also with the toothed gear 43 on the shaft 17 of the inking cylinder 16, (see Fig. 3). The other inking cylinder 26 is driven by two gears 44 and 45 (Fig. 1) mounted to rotate about the swivel axis 30 of the brackets 29 supporting this inking cylinder 26 and one of which, 44, gears with the common driving gear 40 referred to above and the other of which 45 gears with a toothed gear 46 on the shaft 27 of the inking cylinder 26. This enables the inking cylinders 16 and 26 to be driven at different speeds so as to provide a predetermined amount of peripheral slip between them and assists in a smooth and even distribution of the ink on the inking cylinders. The inking cylinder 26 has a surface layer 26a shown in section in Figs. 2 and 3. The printing cylinder 4 is driven by a second toothed gear 47 (Fig. 3) on the shaft 7 of the impression cylinder 6 and each interchangeable printing cylinder 4 has its own driven gear 48 corresponding to the diameter of the cylinder 4 so as to maintain the correct peripheral speed between the printing and impression cylinders 4 and 6. All these gears are located outside the frame 1 of the machine so that they may be readily enclosed by guards or gear casings to enable effective protection and lubrication of the gears to be provided.

It will be seen from the drawings that the shafts 5 of the printing cylinder 4 are well supported in the bearings 2 solidly mounted in the main frame members 1 of the printing machine. The detachable caps 3 of the bearings 2 enable the printing cylinder 4 to be readily removed and replaced by another printing cylinder of different diameter which is then retained in position by replacing the bearing caps 3.

In order to accommodate a different diameter printing cylinder 4, the impression cylinder 6 is moved nearer to or further from the axis of the printing cylinder according to whether the latter is of smaller or larger diameter, than the one being replaced. This movement is effected by causing the brackets 9 to swivel about their pivotal supports 10. For this purpose the shaft 13 is rotated in the appropriate direction so that the toothed pinions 12, gearing with the teeth 11 on the brackets 9 will swivel the brackets about the pivotal supports 10 to the desired extent. This adjustment will not affect the drive of the common driving gear 40 to the toothed gear 42 on the shaft 7 of the impression cylinder 6. Each printing cylinder 4 has a gear 48, the pitch diameter of which corresponds with the effective diameter of the printing cylinder 4 on the shaft 5 on which it is mounted. Thus the gear 47 on the shaft 7 of the impression cylinder 6 will engage correctly with the gear 48 on the shaft 5 of the printing cylinder, which will thereby be driven at the correct speed relatively to the impression cylinder.

The inking cylinder 16 may also be adjusted relatively to the printing cylinder 4 by causing its brackets 19 to swivel about the pivotal supports 10. For this purpose the shaft 21 is rotated in the appropriate direction so that the toothed pinions 22 gearing with the teeth of the quadrants 20, will effect the desired adjustment. The connecting links 32 will cause the brackets 29 to move with the brackets 19 maintaining the relative adjustment between the inking cylinders 16 and 26. The drive to the inking cylinder 16 is effected by the common driving gear 40, which is located on the axis of the pivot 10 and the drive to the inking cylinder 26 is effected by the gears 44 and 45 located on the axis of the pivots 30. The drive is thus not disturbed by adjustment of the inking cylinders relatively to the printing cylinder.

I claim:

1. In a rotary printing machine for a series of interchangeable printing cylinders of different diameters, frame members, rigidly mounted bearings on the frame members, a printing cylinder, shafts at each end of the printing cylinder engaging in the bearings which are spaced closely to the ends of the printing cylinder, an impression cylinder and an inking cylinder, shafts at the ends of the impression and inking cylinders, movable brackets mounted outside the frame members, pivotal supports on the frame members on which the brackets swivel, bearings in the brackets for the shafts of the impression and inking cylinders, means for adjusting the brackets to swivel about the pivotal supports to move the impression and inking cylinders toward and away from the printing cylinder, a toothed driving gear arranged to rotate about the axis of said pivotal supports, a toothed gear on the shaft of the impression cylinder, a toothed gear on the shaft of the inking cylinder to transmit the drive from said first mentioned toothed driving gear to the impression and inking cylinders.

and means for driving the printing cylinder from the impression cylinder shaft.

2. In a rotary printing machine for a series of interchangeable printing cylinders of different diameters, a pair of frame members, rigidly supported bearings in the frame members, a printing cylinder having shafts by which it is detachably supported in these bearings, two pairs of brackets movably mounted outside the frame members, pivotal supports on the frame members about which the brackets swivel, bearings in the brackets, an impression cylinder having shafts engaging the bearings of one pair of brackets, an inking cylinder having shafts engaging in the bearings of the other pair of brackets, means for adjusting the brackets to swivel about the pivotal supports, and additional inking cylinder having shafts engaging in bearings in another pair of brackets movably mounted outside the frame members, pivotal supports on the frame members about which these brackets swivel, adjustable connecting links coupling the brackets supporting each inking cylinder and means for driving the printing cylinder, impression cylinder and inking cylinders.

3. In a rotary printing machine for a series of interchangeable printing cylinders of different diameters, a pair of frame members, rigidly supported bearings in the frame members, a printing cylinder, having shafts by which it is detachably supported in these bearings, two pairs of brackets movably mounted outside the frame members, pivotal supports on the frame members about which the brackets swivel, bearings in the brackets, an impression cylinder having shafts engaging in the bearings of one pair of brackets, an inking cylinder having shafts engaging in the bearings of the other pair of brackets, means for adjusting the brackets to swivel

about the pivotal supports, a second inking cylinder whose periphery engages the first inking cylinder, a further pair of brackets having bearings in which engage the shafts of said second inking cylinder, pivotal supports on the frame members about which these brackets swivel, adjustable connecting links pivoted to the brackets which support the two inking cylinders, a common driving gear mounted to rotate about the common axis of the first two pairs of brackets, gears on the shafts of the impression cylinder and the first inking cylinder, a second gear on the shaft of the impression cylinder, a gear on the shaft of the printing cylinder gearing therewith, two gears mounted to rotate about the axis of the pivotal support of the second inking cylinder, one of which gears with the common driving gear, and a driven gear on the shaft of the second inking cylinder which gears with the other of these two gears.
